[57] CLAIM

The ornamental design for a stand for a water heater, as shown and described.

DESCRIPTION

FIG. 1 is a top plan view of a stand for a water heater showing my new design.

FIG. 2 is a bottom plan view thereof.

FIG. 3 is a side elevational view thereof.

FIG. 4 is a top side perspective view thereof.
FIG. 5 is a top side perspective view thereof also showing a water heater depicted in phantom mounted on the top surface thereof, said water heater forming no part of the invention.
